[57] CLAIM

The ornamental design for a combined wrist watch and tide indicator, as shown and described.

DESCRIPTION

FIG. 1 is a front plan view of a combined wrist watch and tide indicator showing our new design;
FIG. 2 is a front elevational view with the time and moon indicators and bezel in alternate positions;
FIG. 3 is a front elevational view with the time and moon indicators and bezel in further alternate positions;
FIG. 4 is a perspective view thereof from the right side;
FIG. 5 is a bottom plan view thereof;
FIG. 6 is a left side elevation thereof;
FIG. 7 is a right side elevation thereof; and,
FIG. 8 is a top elevation thereof, the bottom elevation being a mirror image of the top elevation.

FIG. 1

FIG. 2
